US0D1075491S

(12) **United States Design Patent** (10) **Patent No.:** **US D1,075,491 S**
(45) **Date of Patent:** **** May 20, 2025**

(54) **SCREW**

(71) Applicant: **INTEGRAL BUILDING PRODUCTS INCORPORATION**, Tainan (TW)

(72) Inventor: **Li-Ching Hsiao**, Tainan (TW)

(73) Assignee: **Integral Building Products Incorporation**, Tainan (TW)

(**) Term: **15 Years**

(21) Appl. No.: **29/909,663**

(22) Filed: **Aug. 9, 2023**

(51) LOC (15) Cl. **08-08**

(52) U.S. Cl.

USPC **D8/387**

(58) **Field of Classification Search**

(57) **CLAIM**

The ornamental design for a screw as shown and described.

DESCRIPTION

FIG. 1 is a perspective view of a screw showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the figures are included for illustrating unclaimed portions of the screw and form no part of the claimed design.

1 Claim, 7 Drawing Sheets
